ORNAMENTAL RAILING

Louis Blum and William J. Horgan, Jr., Pittsburgh, Pa.,
assignors to Blumcraft of Pittsburgh, Pittsburgh, Pa., a
firm

Filed Dec. 19, 1967, Ser. No. 9,848

Term of patent 14 years

(Cl. D13—7)

FIG. 1 is a perspective view looking from one side at a railing embodying our new design;

FIG. 2 is a side view of the handrail portion of a railing embodying our new design;

FIG. 3 is a side elevation of a railing embodying our new design;

FIG. 4 is an enlarged view of the subject matter illustrated within IV—IV of FIG. 3; and

FIG. 5 is a sectional view along the line V—V of FIG. 3.

The dominant features of the design are shown in solid lines.

The railing repeats as indicated and is shown fragmentarily to indicate indeterminate length.

We claim:

The ornamental design for an ornamental railing, as shown and described.
